(57) **CLAIM**

The ornamental design for a funnel cover for breast pump, as shown and described.

DESCRIPTION

FIG. 1 is a perspective view of the top, front, and right side of a funnel cover for breast pump showing our new design; FIG. 2 is a perspective view of the top, rear, and right side thereof;

FIG. 3 is a top plan view thereof;

FIG. 4 is a front elevational view thereof;

FIG. 5 is a right side elevational view thereof;

FIG. 6 is a rear elevational view thereof;

FIG. 7 is a left side elevational view thereof;

FIG. 8 is a bottom plan view thereof;

FIG. 9 is a cross-sectional view thereof along the line 9—9 in FIG. 4; and,

FIG. 10 is a cross-sectional view thereof along the line of 9—9 in FIG. 4; the broken line showing of the pump is shown for environmental purposes only and forms no part of the claimed design.

The portions shown in broken lines are for illustrative purposes only and form no part of the claimed design.
